UNITED STATES PATENT OFFICE.

JOHN W. SADLER, OF GLASGOW, NORTH BRITAIN.

CONSTRUCTION OF SHIPS.

SPECIFICATION forming part of Letters Patent No. 232,651, dated September 28, 1880.

Application filed February 14, 1878. Patented in England June 20, 1877.

To all whom it may concern:

Be it known that I, JOHN WILLIAM SADLER, of Glasgow, in the county of Lanark, North Britain, master mariner, have invented new and useful Improvements in Construction of Screw Steam Ships or Vessels and in their propelling or steering mechanism, which improvements are fully set forth in the following specification, reference being had to the accompanying drawings.

In the drawings, Figures 1 and 2 are a sectional elevation and a corresponding horizontal section, respectively, of the stern part of a screw-steamship, shown as fitted with one modification of my said invention or improvements connected with the screw-propeller and its shaft, gearing, and fittings, and with the stern of the ship and its rudders, and Fig. 3 is a plan, on a large scale, of the screw raising and lowering gear and the rudder steering-gear.

My invention relates to that class of screw-steamships provided with devices adapted for raising and lowering the screw when the vessel is in motion; and it consists in the peculiar construction and management of parts, which will be hereinafter more fully described, and then pointed out in the claims.

In carrying out my invention, I form the large deep narrow part of the keel Z, below the stern, sometimes termed the "dead-wood," (where the screw-shaft usually passes out through a cylindrical tube or channel a little narrower than this portion of the keel,) of two frames, as seen at A A, each with an outer and inner skin or thickness of sheet-plating, A' A'', in iron or steel ships, or of planking in wood vessels, with angle-iron or other frames A''' between them, and a deep narrow longitudinal radial angled or rectangular channel, B B', between the frames A A, formed with or having two vertical stern-posts, A², at the extreme stern, instead of one, as formerly, joined below by a strong sole or frame, B², hollow at b for the water to pass through, with strengthening-ribs b' across, with a deep parallel vertical recess, B', on the inner face of and between the posts A², narrow transversely—that is, just wide enough to allow the long bush or lignum-vitæ-packed bearing-block C of the stern neck-journal d of the screw-shaft

D to be raised to the usual level, as seen at 1 1, or it might be higher out of the water, as indicated by the dotted lines 1 2, or lowered quite down, as indicated at 1 3, to near the 55 level of the keel, all in a new or improved manner, as seen particularly in Fig. 1, so that the screw E, which, under these improvements, is secured and keyed on the extreme or overhanging stern end of the shaft D, so that when the 60 vessel is sailing in deep water it would thus work with its blades quite down below the bottom line z z of the keel Z of the ship in solid water, is not disturbed by the pitching motion or displacement of the ship. The forward 65 end of this stern-length D of the screw-shaft would be connected or coupled by a universal-joint coupling, D', to the back end of the shaft D'', passing out from the engine and engine-room, and when it is desired to get easily at 70 and keep this universal-joint coupling D' dry it would be fitted in the compartment or well B''', close inside or in front of the stern stuffing-box tube F F', passing out through the end B'' of the outer deep recess, B, the stuffing-box F'' of which would be made spherical and formed and fitted in two parts on a deep slide, F''', fitted or mounted on the radially rising and falling ball-tube F F' of the screw-shaft D on and over the strong planed water-tight-jointed end plate, F², jointed and bolted or otherwise secured, with an oblong slot in it over one in the end B'' of the outer channel, B, all with the stuffing-boxes F' and F'' and universal-joint coupling D' within a water-tight partition and dry well or chamber at B''', over which a cover might be fitted on the quarter or under deck, for the engineers getting in to inspect and tighten up the stuffing-boxes F' F'' and connect or disconnect this 90 universal-joint coupling D'.

The said carrying or raising and lowering stern-journal bearing-block C in the screw-shaft D may be formed as a collar and groove bearing, as a thrust-block to take a part of 95 the end-thrust off the universal-joint coupling D', or this could have its central steel ring or disk, D³, with its radial journal-arms D², formed with a hard polished spherical center or ball at D³ between and working in 100 the spheroidal end of the shafts D and D'', which could thus receive the end-thrust in

propelling the vessel forward, and so relieve the strain upon the driving journal-arms D^2 , as seen in Fig. 1.

By one arrangement, as here shown in the drawings, the stern end of the screw-shaft D is raised and lowered through its carrying bearing-block C , which has two lateral journal-arms, c , working in hollow bearings c' in the two deep sliding and carrying brass screw-blocks C' , working in planed recessed guides B' on the inside of the stern-posts A^2 of the stern-frames A A . These deep screw-nuts or bushes C' work on and are carried or raised and lowered each by a strong radial screw shaft or bar, C'' , working in a footstep-bearing, C''' , and upper or neck journal-bearings at C'''' in the stern part of the ship and on a deck-frame, C^x , where the upper ends of the screw-spindles C'' could be fitted with spur-wheels C^2 , turned by a central wheel, C^3 , gearing into the wheels C^2 , and the central shaft of the wheel C^3 can be driven by hand and toothed wheels or screw-gearing, or by small special single or double cylinder engines C^4 for the purpose, as seen in Fig. 3, or chain-wheel and chain from the windlass and hauling deck-engines in common use, or other equivalent gearing may be used instead of the screws C'' for the raising of the stern bearing-block C and shaft D , such as vertical rods fitted with screw or scroll racks, or links or chains worked by ordinary geared screws and scroll-wheels by hand or motive power.

The lateral swiveling stems c of the stern or neck journal bearing-block C might be made long enough to work quite through and through the slide-blocks c' of the carrying or raising and lowering screws C'' when these are fitted to work through these blocks a little abaft or forward from these stems c , and likewise when this bearing-block C is carried or raised and lowered by any of these other arrangements of lifting and lowering gear.

Although the universal-joint coupling D' of the screw-propeller shaft D has been described and shown in the drawings as placed and fitted inside the ship and stern stuffing-box tube F F' , this being preferred for safety in case of breakage and convenience of examination and repair; yet still in many cases, as for the smaller classes of ships or short-voyage vessels, this coupling might be fitted in the outer open chamber, B B , close up to the outer end of the stern stuffing-box tube F F' , which in this case would be of the ordinary stationary construction heretofore used, and not require the ball-and-socket stuffing-box F'' F''' and sliding frame F'''' F^2 , described and shown.

Conjoined with this arrangement of these improvements connected with the propeller two-rudders, G , would be used, mounted to work close up to the stern-frames A A , preferably in a flush line or plane with the outside shell or wall, A'' , of the recessed or double stern-post A^2 B B' , and having the back edge, G' , rather within and so as to work quite clear in front

of and on each side of the stern-posts A^2 and keel Z and propeller E . The rudders would be jointed as usual, but to the vertical part A^3 of the frame A , and would have the upper posts or spindle ends G'' passed up through the bush-frames H on the deck, so as to be worked by any suitable gearing ranged and fitted in a duplicate manner at the top of their rudder-posts on a portable frame, as H , on the deck, as shown in one arrangement detached in section in Fig. 1 and in plan in Fig. 3, each rudder-post G'' having a screw-toothed quadrant segmental wheel, g , fitted on it, working into a screw on a horizontal spindle, g' , revolving in bush journal-bearings h in the frame H , one on each side of the central hand-wheel or tiller-shaft, I , also carried in bush-bearings h' in the top of the frame H , and having a loose wheel, g^2 and g'' , on each end of the shaft I inside the frame, gearing into corresponding pinions g^3 g''' , fast on the screw-spindles g' .

The central shaft, I , which has the steering hand spoked wheel I' keyed on its front end, is bored hollow and fitted with a central screw spindle, i , screwed powerfully out or in a short distance by the hand-wheel i' , working by a collar-nut in its eye on the outer end of the spindle i and in a thrust-socket, i'' , screwed or otherwise secured on the outer end of the shaft I , all so as to shift a duplex or friction grooved clutch, J , mounted on the center of the hollow shaft I , and secured by a collar, j , through a slot in this shaft to the inner end of the screw-spindle i , and so as to take into one or other of the angled groove-and-ring couplings formed on the inner face of each pinion g^2 g'' , according as shifted and screwed up by the hand screw-wheel i' , as desired, after both rudders G G have been placed in a line with the keel, as for engaging and working the port-rudder G , and simultaneously disengaging the starboard one, or, vice-versa, engaging and working the starboard rudder at the same moment and by the same act disengaging the port rudder, the one rudder turning out from the port side and the other from the starboard side to port or starboard the ship, respectively, by the turning of the hand steering-wheel I' , the one having first been turned in toward the line of the keel before the other is turned outward therefrom to so port or starboard the ship. If desired, the rudders may be arranged to swing across or into the water-channel or free water-space in the dead-wood by removing the braces connecting the stern-posts with the frame of the ship at the rudder-posts, or such of those braces as would prevent the free movement of the rudders inward.

The main stern-frames A A behind each rudder G G are formed each with a large open nearly-rectangular recess, a , through them, with strengthening-ribs a' across, all so that in steering the outer water is free to rush up through the openings b in the keel B^2 , into the chamber B B' , and out through these openings a in the keel-frames A A , or out through the

back end, between the stern-posts A², over or under the screw-propeller, all as indicated by the arrows in Fig. 1. It is to be understood, however, that other arrangements of rudder-gearing may be used, such as oscillating or sliding vanes working out through narrow-angled chambers under the port and starboard quarters, the one being projected out into action as the other is drawn in out of action by 10 suitable lever or rack-and-wheel gear.

When twin-screw ships are fitted on this new or improved system, the ordinary arrangement of central rudder would do, and two double-cased vertical radial channels or chambers 15 would be fitted one under each quarter, for the shaft of the port and starboard screw-shafts to be raised and lowered, with the screw-propeller quite forward in advance of the center stern-post, so that the rudders could be put 20 hard a-port or a-starboard without interfering with the action of either screw.

Either or both screw-propellers, separately or simultaneously, could be raised and lowered by the screws or equivalent gearing, as hereinbefore described, to propel the ship in shal-

low water, or, in deep water, to give the improved action or propelling effect described in reference to the single-screw arrangement.

I claim—

1. A steamship or vessel provided with a rudder on each side of the dead-wood working in recesses forward of the stern-post, communicating with the central water-space or channel, said rudders being hung on pintles in the forward sides of such recesses and actuated 30 jointly or independently, substantially as shown and described.

2. A steamship or vessel provided with an open keel or free water-channel, B B, having inlet and outlet water-spaces b a, substantially 35 as and for the purposes shown and described.

3. In a vessel provided with double or starboard and port rudders, the combination therewith of an open keel or free-water channel, B B', having inlet and outlet water-spaces b a, substantially 40 as shown and described.

JOHN W. SADLER.
